UNITED STATES PATENT OFFICE.

JAMES H. PARFITT, OF TIGERTON, WISCONSIN.

PHOTOGRAPHIC-PRINTING FRAME.

1,101,468.

Specification of Letters Patent. Patented June 23, 1914.

Application filed June 6, 1913. Serial No. 772,169.

To all whom it may concern:

Be it known that I, JAMES H. PARFITT, a citizen of the United States, and residing at Tigerton, in the county of Shawano and State of Wisconsin, have invented a new and useful Photographic-Printing Frame, of which the following is a specification.

My invention relates to a printing device to be operated by manual labor, and its object is, to facilitate the labor to such an extent that a single person can operate it and print a larger number of pictures in a given time, than can be printed upon the frames in general use, and it consists of a base or back foundation board having an opening through it, through which light can pass, and adapted to be secured to the side casings of a window in a room, and to which the printing mechanism is secured, such mechanism consisting of a sliding shutter, normally closed over the light receiving opening in the back board, arranged to be opened by the downward pressure of the foot of the operator upon a treadle, a negative and card holding frame secured to the base or back piece between the shutter and printer, and a platen secured to a lever which is hinged to the upper edge of the printing frame to be operated by the printer as the cards to be printed are placed by said printer over the negative to be printed from, a slide being arranged for receiving the cards as they are released from pressure of the platen against the card, and a box into which the cards are directed by the slide.

My invention is shown in the accompanying drawing, in which,—

Figure 1 is a plan of the printing frame base or back board, with the printing frame removed. Fig. 2 is a horizontal section through the parts shown in Fig. 1 below the line *a*, *a*, of said figure. Fig. 3 is a plan of the shutter showing its rear side. Fig. 4 is a vertical transverse section of Figs. 1 and 2 midway their ends upon the line *x*, *x*, thereof, the light excluding shutter being omitted. Fig. 5 is a plan of the rear side of the negative holding and card receiving frame with its springs. Fig. 6 is a central horizontal section of Fig. 5 upon the line *y*, *y*, of Fig. 5. Fig. 7 is a vertical section upon the line *b*, *b*, of Fig. 11, of the negative and card holding and printing frame. Fig. 8 is a plan of a supplemental plate holder and card or film supporter. Fig. 9 is a side elevation of the printing frame secured in po-

sition across a window, and showing its foot operating treadle and printed card chute and receiving box. Fig. 10 is a plan of the inside frame member, shown in Fig. 5, 60 showing its front face with a negative holder and card supporter, bolted in position thereon. Fig. 11 is a cross section of Fig. 5 upon the line *c*, *c*, thereof.

Similar numerals and letters indicate like parts in the several views.

1, indicates a window side casing in a room; 2, the window sill; 3, the sash; 4, the glass; 5, is the base or back board of the printing frame, adapted to be secured in 70 position across the window with screws 6, through suitable holes therein, said piece 5, having an opening 7, for the passage of light from the window.

A printing frame holder is secured to the piece 5 with screws 8, consisting of a board 9, provided with an opening 10, and end and side pieces 11, which space the board 9 from the board 5, those at the side edges being rabbeted and forming grooves 12, within which a shutter 13, is fitted to slide for opening or closing the opening 10, the shutter being kept closed normally by means of coiled springs 14, which connect the shutter with the end pieces 11 by screws 14^a. The 85 shutter is provided with a cord 15, which is secured to the shutter in a suitable manner, as by the loop 16, the cord being carried over a pulley 17, which is mounted to revolve within a bracket 18, and extended 90 downward to near the floor where it is connected to a treadle 19, the treadle being hinged to a block 20, which is adapted to be screwed down upon the floor. The treadle being arranged in position under the window for its easy operation by the foot of the printer, a slight downward pressure thereon will act to open the shutter and it can be kept open as long as said pressure is maintained.

A negative and card holder frame is secured in position over the shutter opening 10, and consists of two distinct frame members, 21 and 22, both being rectangular, the outer frame member being provided around its inside with shoulder 23, upon which the member 22 is supported, and being also provided with buttons or clips 24, and the frame member 22, is provided upon each end piece with a leaf spring 25, pivotally and loosely mounted upon pins or screws 26, the ends of the springs being adapted in length to be

swung under the projecting part of the buttons 24, and thereby detachably holding the two members together. The frame member 22, is provided with an opening 27, the surrounding walls of which are beveled outwardly toward the light receiving openings 7 and 10. This inner frame member can be quickly removed and another with a different sized opening 27, inserted, by swinging the ends of the leaf springs from under the buttons first, and then returning them to that place after another frame member has been inserted. These two frame members when assembled together, are secured to the board 9 by bolts 28, having each two nuts, 29 and 30, spaced apart, a socket 31, being cut in the rear face of the member 21 for receiving the nut 29. Upon the upper and outer edge of the member 21, a cap piece 32 is secured, extending forward from the outside face of filling pieces 32^a, at top and bottom of said member the major portion of an inch. Hinged to this cap piece by hinge 32^b, a hand lever 33 is arranged, having secured thereto by means of a centrally arranged bolt 34, a platen 35, provided with dowels 36, for holding the platen square with the lever, and that others with like positioned dowels may be substituted for this particular size.

To the front face of the member 22, a negative holder 37, is secured by bolts and thumb nuts 38, the negative 39, being clamped between the piece 37 and outside face of the member 22. The outside face of the member 22, being plain, the negative can be adjusted in a vertical or horizontal direction, so that the picture to be printed will be transferred to the card to be printed in a position upon the cards that the taste of the printer requires. The cards to be printed, (indicated in dotted lines inside of the platen 37,) are placed one at a time with an end against the shoulder 40, of the piece 37 and their lower edge resting upon the upper edge of said piece at the left of said shoulder and between the platen and negative, when the printer, taking hold of the handle of the lever 33, presses the platen toward the negative, and at the same time presses downward with the foot upon the treadle which pulls the shutter open and admits the light to the negative for the length of time required. As the cards are printed, they will, upon the loosening up of the platen, drop from the edge of the piece 37 to the slide 42, and then to the box 43. The frame 22 being held within the frame member 21, between the shoulder 23 and buttons 24, by means of the two springs 25, the pressure of the platen against the card, acts upon said springs in such a manner that whatever the thickness, (within reasonable limits), of the negative and card to be printed, the platen will be pressed

evenly over its entire surface against the card.

In making kodak work and printing from films, a clear glass plate is used instead of a negative plate, and a different holder is required from the piece 37. This is shown in Fig. 8, and consists of a piece 44, to be secured to the member 22, with the same bolts and thumb nuts 38, as 37 is, and which is for holding the clear glass plate against the member 22, and is provided with an L shaped piece 45, which is connected thereto by spring clips 46, the piece 45 being adapted for holding a film between it and the glass plate. The clips are permanently secured to the piece 45 with screws or nails 47, and are loosely connected to the piece 44, with round or other shaped thumb nuts 48, the spring of the clips permitting the piece 45 to be sprung away from the glass plate for the insertion of a film.

Having described my invention, what I claim and desire to secure by Letters Patent, is,—

1. A photographic printing apparatus, comprising a base or back board having a light admitting opening intermediate its ends and adapted to be secured to the opposite side casings of a window, a second board of less length than said back board, spaced from and secured thereto, and provided with a light admitting opening similar to and arranged opposite the light opening in said back board, rabbeted spacing blocks at the opposite side edges of said second named board spacing it from said back board, and forming grooves between said spacing blocks and the second named board, a shutter arranged to slide across the window longitudinally of said board in said grooves, springs connecting said shutter and a fixed part, near one end of said second named board and arranged to normally hold the shutter closed over the light admitting opening in said second named board, a pulley arranged at the opposite end of said second named board from said spring fastening end, a treadle arranged in a suitable position for being pressed downward by the foot of the operator, and a flexible member running over said pulley and connecting said treadle and shutter.

2. In a printing apparatus having a base or back board provided with a light admitting opening intermediate its ends and adapted to be secured to the opposite side casings of a window, and a second board of a less length than said back board secured thereto and provided with a light admitting opening similar to and arranged opposite the opening in said back board, spaced from said back board and being provided with a shutter arranged for sliding between said two boards across the light opening in said second named board and normally covering

5 said opening, and means for opening said shutter by the action of the foot of the operator, the combination of a photographic printing frame, provided with an opening
 10 for the passage of light, centrally thereof, means for securing said printing frame to said second named board with their light entering openings opposite each other, said frame consisting of two rectangular members, one within the other, and the inner one of less thickness than the outer one, a shoulder around the inside edges of the outer frame member adapted to support the inner member thereon, buttons, secured at
 15 two points upon the outer face of the larger frame member's longer two side frame pieces, a leaf spring arranged along each of the shorter of the side frame pieces of the smaller member and pivotally connected thereto midway its ends and said ends being
 20 adapted to be swung under said buttons upon the outer member for detachably connecting said two frame members, said inner frame member having its outer face plain
 25 and arranged in a vertical position and adapted to have a negative secured in position over the opening therein, a negative holder and card gage consisting of a piece having a square upper edge for the major
 30 portion of its length, an upstanding shoulder at one end of said square edge, bolts and suitable nuts arranged in position for clamping said piece to the outer face of said inner member with a negative between
 35 it and said outer face, said square upper face serving as a support for a card in printing it.

3. In a photographic printing apparatus, consisting of a base or back board provided
 40 with a light admitting opening intermediate its ends adapted to be secured to the opposite side casings of a window, and a second board of a less length than said back board secured thereto and provided with a
 45 light admitting opening similar to and arranged opposite the light admitting opening in said back board, spaced from said back board and being provided with a shutter arranged for sliding between the two boards
 50 over the opening in said second named board and normally covering said opening, and means for opening said shutter by the action of the foot of the operator, a printing frame provided with an opening for the passage
 55 of light centrally thereof, secured in position across said second named board with

their light admitting openings opposite each other, said printing frame consisting of two members, the inner one adapted to have secured to its outer face over its light admitting opening a negative, and having a resilient movement transversely of said frame within the outer member, a lever vertically arranged and hinged at its upper end to the upper edge of said printing frame, midway its ends, a platen secured to said lever in a position centrally of the light admitting opening in said printing frame, means for securing a negative against the inner member of said printing frame and over the central opening therein, a suitable support for a card to be printed, a suitable receptacle for the printed cards below said printing frame and means for directing the cards as they fall from said support after being printed, into said receptacle.

4. A photographic printing frame adapted to be secured in position across a window where means is provided for controlling the admission of light to said frame, consisting of the frame members 21 and 22, the latter being provided with springs for permitting a transverse movement thereof within the former, and being provided with a light admitting opening centrally arranged through the latter, a negative holder adapted to clamp a negative against the outer face of the opening, a lever hinged at its upper end to the upper edge of the member 21, a platen detachably secured to said lever between it and the outer face of the member 22, opposite its light admitting opening, said negative holder being adapted to receive and support a card to be printed upon a portion of its upper edge.

5. In a photographic printing apparatus, in combination with a member adapted to have the part to be printed from secured against a light admitting opening therein, a holder for said part, adapted to be connected to said light opening member, consisting of the pieces 44 and 45, the latter L shaped and connected to the part 44 with spring clips 46, by means of screws or nails, 47, and detachably secured to the piece 44 by means of bolts and round or other shaped thumb nuts 48.
